ADJUSTABLE PITCH FOR LEVELING INSTRUMENTS

Vincent F. Posthauer, Sr., Glen Oaks, N. Y.

Application September 20, 1954, Serial No. 457,275

6 Claims. (Cl. 33—207)

This invention relates to spirit levels. More particularly, the invention has reference to a device attachable to an end of a level, and adjustable transversely of the level to engage an inclined surface against which the level is supported.

Devices of the type stated are not new per se. However, it is proposed to provide an improved mounting of such a device upon a level, whereby the level can be shifted to a selected position of adjustment speedily and with maximum ease, and can be fixed against movement relative to the level, in said adjusted position.

A further object is to provide means, in one form of the device, for facilitating the reading of the device from in front of rather than from the end of the level.

Another object, in some forms of the invention, is to insure that in its normal, inoperative position, the attachment will be disposed inwardly from the plane of the work-contacting surface of the level, to permit normal use of the level without interference from the attachment.

Yet another object, in another form of the invention, is to incorporate the device directly within the body of the level, so that the transversely adjustable portion of the device will be flush with the end and with the respective longitudinal surfaces of the level, when said portion is in its inoperative, fully retracted position.

A further object is to, in another form of the invention, facilitate the attachment of the device to a conventional level, without requiring modification or redesign of the level, or drilling of any holes in the level.

Another object, in the last-mentioned form, is to permit the adjustable clamping of the device to any of various levels differing from one another in respect to their size or design.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of a level on which has been mounted a pitch-engaging device formed in accordance with the present invention.

Fig. 2 is an enlarged, fragmentary perspective view of the end of the level and of said device.

Fig. 3 is a sectional view on line 3—3 of Fig. 2.

Fig. 4 is a transverse sectional view on line 4—4 of Fig. 1.

Fig. 5 is a transverse sectional view through the level on line 5—5 of Fig. 1.

Fig. 6 is a view similar to Fig. 2 showing a modified form.

Fig. 7 is a sectional view on line 7—7 of Fig. 6.

Fig. 8 is a sectional view on line 8—8 of Fig. 6.

Fig. 9 is a view similar to Fig. 6 showing a second modification.

Fig. 10 is a sectional view on line 10—10 of Fig. 9.

2

Fig. 11 is a fragmentary, exploded perspective view of a third modification.

Fig. 12 is a fragmentary side elevational view of the level with the form of Fig. 11 secured thereto, a portion of the device being shown in section.

Fig. 13 is an enlarged sectional view on line 13—13 of Fig. 12.

In the form of Figs. 1—5, the generally conventional level 14 includes a flat, elongated body 16 on which are formed longitudinal flanges 18 and end flanges 20. Flanges 18 are in parallel planes normal to the plane of body 16, and end flanges 20 are also in parallel planes, normal to the body 16 and perpendicular to the planes of the flanges 18. On body 16, at uniformly spaced locations along the length thereof, bubble assemblies generally designated 22 are provided. Each of these is mounted in a circular formation 23 of the body having a center opening in which transversely spaced, parallel, circular sight windows 24 (Fig. 4) are peripherally fixed, to enclose a pair of bubble tubes 26.

Alternating with the bubble assemblies 22 are elongated, rectangular openings 28 formed in the level to lighten the weight thereof.

The pitch-gauging device 30 constituting the invention includes a rectangular plate 32 integrally formed along one side edge with a flange 34 extending in a plane normal to that of plate 32, and engaging against one side edge of the end flange 20 which plate 32 overlies (Fig. 3).

Formed in plate 32 is a closed longitudinal slot 36, through which extends a combination clamping and mounting screw 38 threaded in an end recess 39 formed in flange 20. A washer 40, interposed between the screw head and plate 32, bears against the plate at opposite sides of slot 36.

On that side edge of plate 32 remote from flange member 34, a calibrated scale 42 is provided, and any of the calibrations thereof may be registered with a single index 44 marked upon the corresponding side edge of the associated end flange 20.

In Fig. 2 the device is inoperatively disposed. As will be noted, at this time, its bottom edge is spaced inwardly to a slight extent from the plane of the work-contacting surface of the bottom longitudinal flange 18. The location of the bottom end of plate 32 inwardly from said plane may be properly found by registering index 44 with the lowermost gradation or calibration 42. At the same time, screw 38 is engaged against the bottom end of slot 36.

In use of the device, and assuming that the inclination from the horizontal of a surface S is to be established, screw 38 is loosened. Plate 32 is then adjusted transversely of the level, that is, downwardly in Fig. 1, until its bottom edge is in contact with surface S with the level 14 extending perfectly horizontally as determined by checking of the proper bubbles. The level now, in cooperation with the device 30, is supported against the surface S at opposite ends of the level, with the level in its horizontal position. That calibration which has, during this process, been registered with index 44 is read. The calibrations will be suitably marked with indicia to designate the degree of pitch per established number of feet. For example, in a commercial embodiment, the gradations may be marked in terms of the number of inches for each two feet of surface S. The level, thus, may be exactly two feet long between the left-hand end of the handle as seen in Fig. 1, and the work-contacting bottom end of plate 32, and the total number of gradations may represent a half inch of drop per two feet of surface S. Of course, the particular manner in which the calibrations are marked can be varied, and they may be marked off, for example, in degrees, instead of in

number of inches of drop per each foot or predetermined number of feet of surface S.

When the device has been adjusted to the proper location, it can be clamped in place by means of the screw 38. Alternatively, the screw may be left slightly loose, so as to be capable of frictionally engaging the plate 32 in the selected position of adjustment, while still permitting manual adjustment of the plate 32 to any other position. The clamping screw may thus be used primarily for fixedly securing the device to the level in the inoperative position of the device shown in Fig. 2.

In Fig. 6, there is shown a modified form wherein the level 14^a has attached thereto a pitch-engaging device 30^a. The device 30^a includes a rectangular, flat base plate 46, having an end to end longitudinal channel in which is slidably mounted the transversely adjustable, scale-marked plate 32^a having calibrations 42^a registrable selectively with an index 44^a of base plate 46. Plate 32^a can be secured in selected positions of slidable adjustment by a clamping screw 38^a about which is composed a washer 40^a adapted to bear peripherally against plate 32^a.

In this form of the invention, base plate 46 is fixedly secured to the adjacent end of level 14^a, by screws 50 threadable into a vertical series of end recesses 39^a of the level 14^a.

The screws have tapered heads, engaging in complementary tapered countersunk openings 54 formed in base plate 46 at the base of its longitudinal channel.

In Figs. 9 and 10, the level 14^b, at one end, has a channel 56 formed therein, extending between the top and bottom or longitudinal surfaces of the level. Sliding in the channel is a plate 32^b, having calibrations 42^b registrable selectively with an index 44^b marked upon the end surface of the level. A clamping screw 38^b holds the plate 32^b in selected positions of adjustment.

In Figs. 11-13 a third modification is shown, adapted for connection to a conventional level 14^c, without drilling or other modification of the level. The device is here designated 30^c, and includes a rectangular base plate 46^c having a longitudinal channel in which slides a plate 32^c suitably calibrated in the manner previously described, and held in selected positions of said slidable adjustment by a clamping screw 38^c threaded into the base plate.

In this form of the invention, the device is provided at opposite sides thereof with arms 58 having at one end longitudinal, closed slots 60 receiving pivot pins 62 carried by and between ears 64 formed upon the opposite sides of the base plate. At their other ends, arms 58 are formed with arcuate spring wings 66 engageable in a circumferential groove 68 formed upon the outer surface of a sleeve 70, medially between the ends of the sleeve. At its ends, the sleeve is knurled to facilitate rotation thereof. The sleeve, at its opposite ends, is formed with internal left and right-hand threads, respectively, threadably engaged with complementary, oppositely threaded studs 72, 74 having feet 76, 78 fixedly secured to the outer ends thereof. The feet are of rectangular, block-like formation.

In use of this form, it is necessary, to attach the device to the level, only that the user swing the arms 58 outwardly from the position shown in Fig. 11, after which the base plate 46^c is positioned against the adjacent end flange 20^c of the level. The arms 58 are now swung inwardly, after which the arms can be adjusted in the direction of their lengths to cause the feet 76 to engage against the inner surface of the flange 20^c.

With the feet 76, 78 engaged against the inner surface of flange 20^c of the level, and with the feet also in engagement against the opposite sides of the body 16^c due to the inward swinging movement of the arms, the user rotates the sleeves 70, to adjust the feet away from one another. Ultimately, the outer or end surfaces of the feet engage against the inner surfaces of the longitudinal

flanges 18^c, and continued efforts to rotate the sleeves 70 in the same direction will cause the feet to bind tightly against said longitudinal flanges of the level.

By reason of this arrangement, the device is fixedly secured to the level, without any necessity of drilling holes in the level or otherwise modifying the same. Further, it is quite important to note that the particular clamp which has been devised for this purpose is so designed as to prevent movement of the base plate 46^c in a vertical direction upon the level, from the proper position of said base plate, in which proper position its ends are flush or are even spaced inwardly a short distance in respect to the outer surfaces of the longitudinal flanges 18^c.

As will be noted, the pivot pin 62 is provided with a wing nut, thus to permit said wing nut to be turned to force the ears 64 tightly against the opposite surfaces of the arm 58, to hold the arm in selected positions to which it is pivotally and slidably adjusted with respect to said ears. This further insures that the base plate will be held in proper position against the end of the level body.

The adjustable clamping arrangement illustrated and described has the further desirable characteristic, that it permits a single form or size of the device to be clampably engaged with any of various levels, different from one another with respect to their particular size. It is necessary only that the level be of the general type shown in Figs. 11 and 12, this being perhaps the most popular type of level in use today.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

40. 1. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst.
45. 2. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst.
50. 3. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level.
55. 4. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level.
60. 5. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level.
65. 6. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level.
70. 7. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level.
75. 8. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level.

the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level, said last-named means extending perpendicularly to the arms so as to engage against longitudinal flanges provided upon the level.

4. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level, said last-named means extending perpendicularly to the arms so as to engage against longitudinal flanges provided upon the level, and being adjustable as to length correspondingly to the distance between said longitudinal flanges.

5. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level, said last-named means extending perpendicularly to the arms so as to engage against longitudinal flanges provided upon the level, and means on said arms engageable with the level to hold the base plate in position thereagainst, said arms having a sliding and pivotal connection to the base plate for adjustment of the last-named means and arms longitudinally of the level with the base plate in engagement with the end surface of the level, said last-named means extending perpendicularly to the arms so as to engage against longitudinal flanges provided upon the level, and being adjustable as to length correspondingly to the distance between said longitudinal flanges.

larly to the arms so as to engage against longitudinal flanges provided upon the level, and being adjustable as to length correspondingly to the distance between said longitudinal flanges, said last-named means including a sleeve rotatably mounted upon each arm and having internal, opposite threads at its opposite ends, said last-named means further including oppositely threaded studs engaged in the ends of the sleeve.

6. An adjustable pitch-gauging attachment for a spirit level comprising means connectable to a level at one end thereof, and a plate in engagement with said means and adjustable transversely of the level beyond one side thereof into engagement with an inclined surface the pitch of which is to be established, said means including a base plate, clamping arms carried by said base plate at opposite sides thereof and swingable toward and away from the opposite faces of the level when the base plate is positioned against one end of the level, and means on said arms engageable with the level to hold the base plate in position thereagainst, said arms having a sliding and pivotal connection to the base plate for adjustment of the last-named means and arms longitudinally of the level with the base plate in engagement with the end surface of the level, said last-named means extending perpendicularly to the arms so as to engage against longitudinal flanges provided upon the level, and being adjustable as to length correspondingly to the distance between said longitudinal flanges, said last-named means including a sleeve rotatably mounted upon each arm and having internal, opposite threads at its opposite ends, said last-named means further including oppositely threaded studs engaged in the ends of the sleeve, and feet formed upon the outer ends of the studs engageable against said longitudinal flanges and further adapted to engage against the opposite faces of the body of the level and against the inner surface of an end flange of the level against which the base plate is engaged.
